(57) **CLAIM**

The ornamental design for a device for administering medication, as shown and described.

DESCRIPTION

FIG. 1 is a perspective view of a device for administering medication.

FIG. 2 is a top view of a device for administering medication. FIG. 3 is a left side elevational view of a device for administering medication.

FIG. 4 is a front elevational view of a device for administering medication.

FIG. 5 is a right side elevational view of a device for administering medication.

FIG. 6 is a back view of a device for administering medication.

FIG. 7 is a bottom view of a device for administering medication.

FIGS. 8-10 are exploded views of a needle cap disengaging from a lower handle of the device for administering medication as shown in FIG. 1.

FIG. 11 is a perspective view of a needle cap.

FIG. 12 is a perspective view of a needle cap.

FIG. 13 is a top view of a needle cap.

FIG. 14 is a left side elevational view of a needle cap.

FIG. 15 is a front elevational view of a needle cap.

FIG. 16 is a right side elevational view of a needle cap.

FIG. 17 is a back elevational view of a needle cap; and,

FIG. 18 is a bottom view of a needle cap.

The dashed lines immediately adjacent to the claimed areas in FIGS. 9 and 10 represent the boundaries of the claimed design. and form no part of the claimed design.
